UNITED STATES PATENT OFFICE.

JOHN W. VAN DYKE AND WILLIAM M. IRISH, OF PHILADELPHIA, PENNSYLVANIA,
ASSIGNORS TO THE ATLANTIC REFINING COMPANY, OF PHILADELPHIA, PENN-
SYLVANIA, A CORPORATION OF PENNSYLVANIA.

PROCESS OF AND APPARATUS FOR DISTILLING PETROLEUM.

1,095,438.

Specification of Letters Patent.

Patented May 5, 1914.

Application filed April 18, 1911. Serial No. 621,905.

To all whom it may concern:

Be it known that we, JOHN W. VAN DYKE and WILLIAM M. IRISH, both citizens of the United States, residing at Philadelphia, in the county of Philadelphia and State of Pennsylvania, have invented certain new and useful Improvements in Processes of and Apparatus for Distilling Petroleum, of which the following is a specification.

10 This invention relates more particularly to the distillation of petroleum in the form of an undistilled residue for obtaining therefrom a wide range of products in the same run; the distillation being performed at least in part at the high temperatures necessary to evaporate hydrocarbons with boiling points above 600° F. or above the temperature of commencement of cracking when this is below 600° F.; but the invention extends 15 also to such distillation of petroleum in the form of a distillate and to other distillations of distillate and of undistilled petroleum.

20 Each of the improvements composing the invention is intended to be secured for all 25 the uses to which it can be applied, with or without modification.

25 The object of the invention is mainly to enable the early runnings of distillate in distilling a charge of oil to be obtained in a 30 purer state than that in which they would be apt otherwise to be.

35 At the end of each run, before opening the still for cleaning it out in preparation for a new run, it has been the practice (which we retain) to fill the still with free steam, in order to expel therefrom the hydrocarbon vapors which then occupy the still. In prior 40 current practice these vapors with the steam have been passed through the regular vapor passage; and, being carried by the steam into all parts of the condensers, they have 45 condensed on the walls thereof and have remained (as we have discovered) in part at least attached thereto until dissolved off by the distillate which constitutes the earlier 50 runnings of the next run. Their presence in said earlier runnings of distillate is particularly objectionable where a wide range of products is obtained in the same run (as in a continuous complete distillation of crude 55 petroleum); because the vaporized hydrocarbons in the still at the end of a run in such case are, in gravity, color and properties, so far removed from those which com-

pose the earlier runnings of the next run, 55 that even a small proportion of the former manifests itself in the latter and may make it necessary to redistill an otherwise satisfactory distillate. In any case, there would necessarily be a certain deterioration of said 60 earlier runnings.

65 In accordance with the present invention, the vapors in the still at the end of each run are not allowed to pass on to the regular condensers, but are discharged mingled with the steam through a side passage adapted to that purpose, the same being arranged with special reference to the disposal of a comparatively small quantity of heavy vapors mixed with steam and best leading to a 70 special condenser and receiver; so that the first distillate of the next run is received from the regular condenser free from any of the hydrocarbons composing the so expelled vapors. If desired, also, more or less vapors 75 before the termination of the run can be passed over through the same side passage. Where there is a series of condensers any one or more of these can be protected by withdrawal of vapors through such side passage before they reach the condenser or condensers. It is less important to keep 80 contaminating vapors from condensers from which condensate is to be returned to the oil in distillation than those from which distillate is to be received; but it is considered best to protect each condenser; since this can be done without more difficulty. The distillation which precedes the expulsion of the vapors as herein claimed is primarily de- 85 signed to be performed under atmospheric pressure and without introduction of steam or other aeriform fluid into the still; but working under other pressures (as under partial vacuum, for example) and with in- 90 jection of steam or other aeriform fluid into the still, or with either of these features separately, may to some extent at least be employed, if so desired.

95 The invention comprises all and singular 100 the new, useful and original parts, improvements and combinations herein claimed, whether of process or of apparatus. The accompanying drawing is a view partly in perspective and partly in vertical (longitudinal and cross) sections of a distilling apparatus in accordance with the present invention.

The still *a* is shown in the form of a horizontal cylinder to be heated by fires beneath and to be well jacketed for protection against loss of heat externally. There is a pipe *g* for filling the still with oil and a pipe *h* for conducting away the vapors to the regular condensing means. This vapor pipe *h* is connected with the vapor space of the still *a* by means of a short upright pipe *i* having a removable cover *k*. A side opening receives the end of the vapor pipe *h*. Below said side opening is a flap valve whose operating handle is seen at *l*; and below said valve is another side opening which receives the pipe *m*, a continuation of which is formed by pipe *n* having a valve *p*. In running the flap valve is open and the valve *p* closed. At the end of a run, when steam is introduced into the still to expel the vapors therefrom, their positions are reversed.

The pipe *q*, which joins the pipe *m*, is provided with a safety valve *r* and a vacuum valve *s*. A pipe *t* is provided for introducing steam into the still at the end of a run before opening the manholes (one of which is shown at *u*) for cleaning out. As shown the vapor pipe *h* leads to a condenser in the form of numerous pipes *2* arranged in parallel between header *3* and chamber *4*. A light valve *6* in which a strictured outlet *5* is formed for the vapors may advantageously rest by its own weight over the end of each of a number of such pipes; so that the lifting of one or more of said valves *5* may relieve the pressure in said pipes *2*, should it tend to exceed the predetermined limit. There may be such a valve for each of said pipes; but the pressure could, of course, be relieved without having so many valves. The pipes *2* are inclosed in a casing *7* which fits around the header *3* at the top and has inlet openings *8* at the bottom for inflow of air from the surrounding atmosphere. Each inlet is provided with a valve *9*, which can be opened, wholly or in part, or can be completely closed, as may be desired. Air currents are produced in the casing *7* by heat absorbed from the walls of pipes *2*. The chamber *4* is provided with a non-conducting (or heat retaining) jacket *10*. In the chamber *4*, resting on the grate *11*, are pieces *12* of solid material, say cobble stones of four to eight inches in diameter. The vapor pipe *h* leads from the still directly to the space in chamber *4* below said grate *11*. The vapor outlet of the condenser *2*, *3*, *4* is connected by pipes *13* with the vapor inlet of a second partial condenser *14* composed of numerous pipes set between headers and exposed to the air for cooling.

While dimensions and proportions can be varied, good results have been attained for a still holding a thousand barrels of oil up to the usual level with an air cooled condenser having fifty six of the pipes *2*, each

eleven feet in length and four inches in external diameter (giving about 665 square feet of cooling surface on the closely approached heat conducting walls of pipes *2*). A circular vapor outlet opening *5* of an inch and a quarter diameter would suffice for each pipe *2*, the vapor pipe *h* having an internal diameter of twelve inches and the valves *6* weighing about thirty three ounces each.

The vapor outlet from condenser *14* is connected by pipe *15* with a water cooled condenser, shown in the form of a coil *16* placed in a water tank *17*, which is supported on walls *18* and cross beams *19*. Thus, as shown, the vapors from the still *a* flow successively through two partial condensers each of them cooled by aeriform fluid, and then through a water cooled condenser.

The liquid outlets *20* and *21* of the partial condensers are respectively connected through U traps with the valved draw off pipes *22* and *23* placed in water tank *17*. A valved draw off pipe *24* and a run back *25* (leading to the still *a*) are also connected with the liquid outlet *20*. At *26* is a cover to exclude rain, in case the still stands out of doors. A valved pipe *27*, shown in dotted lines, can be used as a run back, if desired, between the condenser *14* and the still *a*.

The present invention is primarily designed for (but is not restricted to) a complete distillation of crude petroleum in a continuous run, which is one of the modes set forth in our application of October 4, 1909, No. 520,937; of which application the application for the present patent is a division and continuation, the division being made solely in consequence of official requirement. In carrying out such complete distillation, as also generally in carrying out the respective inventions hereof and of our said application 520,937, it is advantageous to employ procedures and appliances of condensation which are arranged for separating from each other hydrocarbons that are vaporized together; and it is most advantageous so to employ those procedures and appliances of condensation which are disclosed herein and in our said application 520,937 and in our application of April 18, 1911, No. 621,904 and are recited in the claims of this last mentioned application. This last is likewise a division and continuation of our application 520,937, the division being made solely in consequence of official requirement. Other known or suitable procedures and appliances of condensation (as well as those last above mentioned) can be used in carrying out the respective inventions hereof and of our said application 520,937.

The expulsion of the vapors from the still at the end of a run and the appliances for accomplishing such expulsion, as recited in

the claims hereof, are no part of the invention of our application 520,937 as restricted in view of the official requirement of division or of the invention of our application.

5 For a complete distillation in a continuous run, the still *a* is supplied with the proper charge of crude oil (say a thousand barrels) and is heated by fires underneath to vaporizing temperatures; and the heating is continued with gradual rise of temperature until the still contents become dry or nearly so, wax tailings (of a gravity equivalent to 10° B. or heavier at 60° F.) coming over as the last distillate. While the oil in the still is 10 attaining a temperature of say 600° F. the temperature in header 3 may well rise to above 400° F. (480° F. was observed in a test run); and as the oil in distillation rises above 600° F. (say finally to 850° F., which 15 has been observed) the temperature in the header 3 would best be between 400° F. and 600° F. (temperatures of from 470° F. to 607° F. were observed in said test run); although near the end of the run the flow of 20 vapors may become so small that the temperature in said header 3 would fall below 400° F. (317° F. was observed in said test run).

The condensate formed in the condenser 2, 30 3, 4 is returned to the still *a* during the earlier part of the run, say until the oil in distillation attains a temperature of about 700° F. (the run back 25 being then open, and the draw offs 22 and 24 closed). After- 35 ward the run back 25 is closed; and the condensate from condenser 2, 3, 4 is collected as distillate through the draw offs 22 and 24, running through the former while it remains sufficiently fluid to do so.

40 The air inlet valves 9 would be more nearly closed at the beginning of each run, when light hydrocarbons are being distilled, and also at the end of each run when the volume of vapors is comparatively small, than 45 they would be during the intermediate part of the run. In other words, the currents of cooling fluid are controlled to increase and decrease in a general way the cooling effect on the vapors according to the varying volume and temperature of the latter. Said air inlet valves 9 would also be closed more when the weather is cold or windy and less (if at all) when it is warm or still. The valves 9 can also be manipulated to counteract or to compensate for other variables. In general observation of the streams from the respective condenser outlets, with test of samples if thought expedient, should give sufficient indications.

In the test run, herein above referred to, after bringing in the still, 147 barrels of distillate were received from condenser 16 and 211 barrels from condenser 14 during the time (19 hours and 20 minutes) in which the oil in distillation was attaining 600° F., an

average collection of distillate from both condensers of 18½ barrels per hour. In the same run, 15 barrels of distillate were received from condenser 16 and 203 barrels from condenser 14 during the time (18 70 hours) in which the oil in distillation was rising from 600° F. to about 700° F., an average collection of distillate of 12½ barrels per hour. In the same run, 64 barrels of distillate were received from condenser 16 and 113 barrels from condenser 14 and 257 barrels from condenser 2, 3, 4 during the time (17 hours) in which the run was completed after the oil in distillation had attained about 700° F., an average collection from 80 the first two condensers of 11½ barrels per hour and from all three condensers of 27½ barrels per hour.

At the end of the run the valve *p* in pipe *n* is opened and the valve *l* is turned to close 85 the ordinary vapor pipe *h*. Steam is then introduced through the pipe *t*. It fills the still *a* and expels the hydrocarbon vapors. They pass, with steam, through the pipes *m* 90 *n* to any desired place or receptacle without entering the condenser 2, 3, 4, the condenser 14, or the condenser 16; so that at the next run the first runnings of condensate are not composed in part of hydrocarbons expelled by the steam. So far as concerns the condensate from condenser 2, 3, 4, as this returns to still *a*, the presence in it of said hydrocarbons would be of small importance; and it is, therefore, of minor importance for the valve *l* and valved branch pipe *n* to be 95 100 between condenser 2, 3, 4 and the still *a*. After expulsion of hydrocarbon vapors, the steam is shut off; and the still *a* is allowed to cool, is opened, is cleaned, is closed and then receives a new charge of petroleum. 105

Were the side passage *n* to remain closed and the regular vapor pipe *h* to remain open during the expulsion by steam of the vapors from the still *a*, the heavy hydrocarbons would (according to our experience) be carried in part even into the water cooled condenser 16 and would remain adherent to the surfaces of said condenser 16, as well as of the condensers 14 and 2, 3, 4. At the beginning of the next run, the heavy hydrocarbons in condenser 2, 3, 4 would be washed back into the still by the returning condensate; but the distillate received from the remaining condensers would be deteriorated by the heavy hydrocarbons which they would dissolve from the condenser surfaces. By 110 using the run back 27 and opening it at the beginning of the next, the heavy hydrocarbons could be washed back into the still; but there would then be a loss of time (and consequently an expense) which it is desirable to avoid; and the distillate from condenser 16 would still be contaminated by the heavy hydrocarbons which the steam would carry 120 over into it.

125 130 135

We claim herein as our invention or discovery:

1. The improvement in distilling petroleum, consisting in closing communication at the end of a run between the still and a distillate condenser, opening at such time also a passage leading elsewhere and not to said condenser, and introducing free steam into the still to expel the vapors then remaining therein without introducing them into said condenser, so that the early runnings of distillate in the next run shall be free from hydrocarbons composing the so expelled vapors, substantially as described.

2. The improvement in distilling petroleum, consisting in conducting the vapors during a run from the still to means for condensing said vapors therein as distillate, closing communication at the end of the run between the still and said means, opening at such time a passage leading elsewhere and not to the said condensing means, introducing free steam into the still to expel the vapors then remaining therein without introducing them into said condensing means, charging the still with petroleum for a new run, conducting vapors again to said means, condensing them therein as distillate, and so continuing, substantially as described.

3. The improvement in distilling petroleum, consisting in charging a still with oil whose hydrocarbons have a wide range of boiling points, heating the same with gradual rise of temperature until vapors to give a wide range of products have passed over, condensing such vapors largely at least in the same condensing means, closing communication at the end of the run between the still and a distillate condenser, opening at such time also a passage leading elsewhere and not to said condenser, and introducing free steam into the still to expel the vapors then remaining therein without introducing them into said condenser, so that the early runnings of distillate which flew from said condenser in the next run shall be free from hydrocarbons composing the so expelled vapors, substantially as described.

4. Apparatus for distilling petroleum, consisting of a still, a valved steam pipe opening into said still, a condenser for distillate, a vapor pipe leading from said still to said condenser, a passage leading away from said still without leading to said condenser and arranged with special reference to the disposal of vapors expelled from the still at the end of each run, and means whereby the vapor contents of said still can at will either be directed into said condenser or be discharged elsewhere while shut off from the latter, substantially as described.

5. Apparatus for distilling petroleum,

consisting of a still, a valved steam pipe opening into said still, a condenser for distillate, a vapor pipe leading from said still to said condenser, a passage branching from said vapor pipe and leading away from it without leading to said condenser and arranged with special reference to the disposal of vapors expelled from the still at the end of each run, and means arranged in one position of the same to close said passage and open communication between the portions of said vapor pipe on the still side and the condenser side respectively of said means and in another position to open said passage and close such communication, substantially as described.

6. The improvement in distilling petroleum, consisting in charging a still with oil whose hydrocarbons have a wide range of boiling points, heating said oil conductively in order to evaporate therefrom hydrocarbons with a wide range of boiling points, conducting the vapors of such evaporation through a number of condensers connected in series and maintained at different temperatures so as to form condensates therein of different gravities corresponding with the respective condensers of the series, withdrawing said condensates separately from each other, subsequently closing communication between the still and a condenser in which condensate of relatively lighter gravity is formed, opening at such time a passage leading elsewhere and not to the last mentioned condenser, and while said communication is closed and said passage open introducing free steam into the still to expel the vapors then remaining therein without introducing them into the last mentioned condenser, substantially as described.

7. Apparatus for distilling petroleum, consisting of a still arranged for its contents to be heated conductively, a valved steam pipe opening into said still, a number of condensers connected with each other in series and arranged to be maintained at different temperatures and one of them connected with the vapor space of said still so as to form condensates of different gravities corresponding with the respective condensers of the series, means for withdrawing said condensates separately from each other, means for closing communication when required between said still and a condenser in which condensate of relatively lighter gravity is formed, a passage leading from the vapor space of said still elsewhere and not to the last mentioned condenser and arranged with special reference to the disposal of vapors expelled from the still at the end of each run, and means for opening said passage when required, so that the vapors in said still can be expelled by steam without introducing them into the last mentioned condenser, substantially as described.

8. The improvement in distilling petroleum, consisting in charging a still with oil whose hydrocarbons have a wide range of boiling points, heating said oil conductively in order to evaporate therefrom hydrocarbons with a wide range of boiling points, conducting the vapors of such evaporation through a number of condensers connected in series and maintained at different temperatures so as to form condensates therein of different gravities corresponding with the respective condensers of the series, withdrawing said condensates separately from each other, subsequently closing communication between the still and that portion at least of the condenser series in which condensate of lighter gravity is formed, opening at such time a passage leading from the vapor space of the still elsewhere and not to said portion of the condensing means in which condensate of lighter gravity is formed, introducing free steam into said still while said communication is closed and said passage open in order to expel the vapors then remaining in said still through said passage without letting them into said portion of the condenser series, recharging said still with oil to be distilled, closing said passage, opening said communication between said still and said series of condensers, heating said oil conductively in order to evaporate the same, conducting the vapors of such evaporation through said series of condensers, withdrawing the condensates separately from each other, and returning for a time condensate to the oil in distillation from that portion of the condenser series in which condensate of heavier gravity is formed, that portion of the condenser series in which condensate of lighter gravity is formed being thus protected against ingress of heavier hydrocarbons during each run by the previous condensation of the latter in the warmer portion of the condenser series and during the expulsion of the vapors by free steam at the close of each run by the discharge of the vapors at such time through said passage, and that portion of the condenser series in which condensate of heavier gravity is formed being washed at the beginning of each run by condensate that is temporarily returned to the oil in distillation, substantially as described.

9. Apparatus for distilling petroleum, consisting of a still arranged for its contents to be heated conductively, a valved steam pipe opening into said still, a number of condensers connected with each other in series and arranged to be maintained at different temperatures and one of them connected with the vapor space of said still so as to form condensates of different gravities corresponding with the respective condensers of the series, means for withdrawing said condensates separately from each other and for temporarily returning condensate to the oil in distillation from that portion of said condenser series in which condensate of heavier gravity is formed, means for closing communication when required between said still and that portion at least of said condenser series in which condensate of lighter gravity is formed, a passage leading from the vapor space of said still elsewhere and not to said portion of the condenser series in which condensate of lighter gravity is formed and arranged with special reference to the disposal of vapors expelled from the still at the end of each run, and means for opening said passage when required, so that that portion of the condenser series in which condensate of lighter gravity is formed can be protected against ingress of heavier hydrocarbons during each run by the previous condensation of the latter in the warmer portion of the condenser series and during the expulsion of the vapors by free steam at the close of each run by the discharge of the vapors at such time through said passage, and that that portion of the condenser series in which condensate of heavier gravity is formed can be washed at the beginning of each run by condensate that is temporarily returned to the oil in distillation, substantially as described.
